UNITED STATES PATENT OFFICE.

CLARENCE H. MARANVILLE, OF AKRON, OHIO.

RUBBER GLOVE.

Application filed September 15, 1923. Serial No. 662,938.

To all whom it may concern:

Be it known that I, CLARENCE H. MARANVILLE, a citizen of the United States, residing at Akron, in the county of Summit and State of Ohio, have invented a certain new and useful Improvement in a Rubber Glove, of which the following is a full, clear, and exact description, reference being had to the accompanying drawings.

10 The general object of the present invention is the provision of a mitten or glove adaptable for use in cleansing garments of fine texture. More specifically my invention is concerned with the provision of a rubber glove having a palm side and back side zones or clusters of irregularly grouped spurs or projections which, when the glove is worn upon the hand of the user may lie adjacent the palm side of the hand when the hand 15 grasps a garment. A further object is the provision of a novel method for economically manufacturing such a rubber glove. Other objects of my invention will hereinafter be set forth in the following description which 20 refers to the accompanying drawings illustrating a preferred embodiment thereof. The essential characteristics are summarized in the claim.

In the drawings, Fig. 1 is a plan view of 30 a glove made in accordance with my invention and showing the palm side of the glove; Fig. 2 is a similar view showing the back side of the glove; Fig. 3 is a view illustrating the manner of wearing and using the glove 35 when washing garments of fine texture; Fig. 4 is a large cross-sectional view taken substantially along the lines 4—4 of Fig. 1; Fig. 5 shows the use of a pair of gloves.

In cleansing garments of fine texture it is 40 usually the domestic custom to rub the garment between the knuckles and palms of the hands, using of course, water and soap as a cleansing medium. When the soap contacts with the skin of the hands, however, it acts 45 as a lubricant and it becomes necessary to firmly grasp portions of the garment and thus clean the garment by rubbing it between the knuckles.

Attempts have been made to manufacture 50 a mitten or glove for this purpose wherein waterproof leather or fabric was used, there being roughened surfaces provided on the glove or pieces of rope or similar material, formed to give a crude representation of a washboard.

My invention contemplates the provision of rubber gloves having cleaning or rubbing surfaces irregularly formed thereon, which are formed on the gloves in such positions that when the glove is being worn for the 60 purpose of cleaning garments, these roughened surfaces will lie adjacent to each other, particularly when the hands are doubled into fist form when gripping a garment. In the present instance, I form a glove of rubber by modern approved methods whereby the palm side of the fingers of the glove are of the usual form as well as the major portion of the palm, whereby the glove walls may be sufficiently thin to permit the use 70 thereof for other purposes than herein specified.

Figs. 1 and 2 show a rubber glove A, which may be formed in various sizes whereby the thumb portions B, and finger portions C may always snugly fit the wearer's hand.

Upon the palm of the glove adjacent the thumb portion B, I form a cluster of irregularly arranged projections of varying height 80 as is shown at D and a similar cluster E adjacent the little finger portion C, these clusters being formed closer to the wrist portion F of the glove than to the thumb and finger portions. As shown in this figure, the 85 thumb portion B and the palm side and ends of the finger portions C, are not encumbered in any manner whereby the sensibility of the hand is not lost to the wearer when handling objects.

Upon the backs of the finger portion C, I form similar clusters or projections E which will lie immediately over the first knuckle of each finger when the glove is worn by the user, whereby when the fingers are folded to 95 represent a fist, as shown in Figs. 3 and 5 the clusters G are brought into juxtaposition with the palm clusters D and E. The palm side of the thumb portion B may have a similar zone of clusters K formed thereon. 100

Each set group of clusters may comprise outer rows of slight projections H and inner rows of projections J, each row of projections being slightly greater in height than its adjacent outer row, thus facilitating 105 the contacting or rubbing of the various projections with the surfaces of the fabric being cleansed.

An article such as I describe may be very 110 economically manufactured by using forms

corresponding to the size of glove to be made, which forms may be dipped in a liquid rubber compound; the number of dippings depending upon the thickness of wall desired in the glove. The clusters G, E, etc., are preferably made in molds in the form of patches of semi-cured or uncured rubber. These patches may then be applied to the form carrying the uncured dipped rubber before the form is submitted to the curing operation. The forms may then be subjected to either a gas cure or an acid dip cure, whereupon the patches become vulcanized to the glove wall. The glove may then be stripped from the form.

If desired, the gloves may be formed in molds in which case the clusters would then be directly molded on the rubber wall, thus eliminating the necessity of separately forming the patches. I find, however, that the form dipping process is more economical and that the patches become thoroughly vulcanized to the finger and palm walls of the glove and remain so throughout the life of the use thereof.

From the foregoing description of my invention it will be readily seen that I provide a rubber glove, particularly adaptable for use in cleansing garments of fine texture, that the glove is formed in such manner that an extreme degree of flexibility is obtained, and incidently when in use does not deprive the user of the glove of sensibility when

handling objects. The disposition of the irregular rubbing surfaces is such that the glove may be used for any of the usual domestic purposes to which rubber gloves are adaptable. It will also be seen from the foregoing description of my invention that a very practical glove construction is afforded which is very durable and which may be very economically manufactured, and furthermore that the rubbing surfaces are formed on the glove in such a manner as to be extremely effective in quickly cleaning fine texture garments without any resulting damage thereto.

It should be particularly noted that by forming the glove on a dipping form, and then applying molded portions having irregular roughened surfaces affords a very economical method of producing thin walled rubber articles having thickened wall zones at the places where the article is subjected to the greatest wear.

I claim:

A glove comprising an all rubber body having finger and thumb portions, such portions having thickened walls in zones, said thickened zone portions having projections extending from the surface thereof and the thickened portions being integral elastic portions of the glove body.

In testimony whereof, I hereunto affix my signature.

CLARENCE H. MARANVILLE.
